UNITED STATES PATENT OFFICE.

JEROME A. CROSS, OF FULTONVILLE, NEW YORK.

HAY-CARRIER.

SPECIFICATION forming part of Letters Patent No. 407,924, dated July 30, 1889.

Application filed August 29, 1888. Serial No. 284,043. (No model.)

To all whom it may concern:

Be it known that I, JEROME A. CROSS, of Fultonville, Montgomery county, New York, have invented a certain new and useful Improvement in Hay-Carriers, of which I declare the following to be a full, clear, and exact description, reference being had to the accompanying drawings, forming part of this specification.

10 This invention is in the nature of an improvement in hay-carriers; and the invention consists of a hay-carrier with its several parts constructed and combined in the manner herein particularly described, shown, and 15 claimed.

In the accompanying sheet of drawings, Figure 1 is a side elevation, partly in section, of the carrier mechanism. Fig. 2 is a plan of the carrier mechanism; Fig. 3, a section in the 20 plane $\alpha\alpha$, Fig. 2; Fig. 4, a side elevation of carriage and pivoted bracket; Fig. 5, a plan of pivoted bracket.

Similar letters of reference indicate like parts in the several views.

25 This invention relates particularly to that class of hay-carriers constructed so as to permit the load to travel freely to the right or to the left of a given position.

The track A of my carrier may be substantially the same as the track used for any similar contrivance. Resting on this track are flanged trolley-wheels B. These wheels are suitably journaled to the carrier-frame C. Also journalled to this frame, but below the 30 wheels B, are grooved pulley-wheels D D. The frame C is provided with lugs a, which form bearings for a pivot-bar b, and this pivot-bar unites and supports the two jaws of a latch E. Also to these lugs a are pivoted pawls 35 p, each having a set-screw r and spring s. Surrounding the pivot-bar b of the latch E is a spiral spring c, with uncoiled ends, forming arms d, that rest against the inner faces of the latch E, so that when the upper legs e of 40 the latch are brought together by compression the sides of the lower part f of the latch will be spread apart, and vice versa. Each jaw of the latch, at or near the lower end f of the same, is provided with a lug g. Also fixed 45 to the track A and spanning the same is a bracket h, and to the bow of this bracket is

secured a double catch F. This catch is of the form shown in Fig. 2—that is, having flaring jaws k, with inclined edges, throats l, shoulders m, and a clearway n.

55 Passing over the grooved pulley-wheels D D is a rope G, and rove into the bight t of this rope is a traveling pulley H. This pulley has in each side of its shell an opening l, and to the lower part of the shell is fixed a clevis w. In the rope G, and on the right and left hand sides, respectively, of the pulley H, are formed ovoid enlargements y.

The rope G, extending on either side of the pulleys D D, passes around pulleys J J, and 65 thence around pulleys K K, the two last-named pulleys being fixed to the floor of the barn or elsewhere by screw-bolts u u and clevises 2 2. The rope, after passing around the pulleys K K, has one or the other of its 70 free ends 3, as may be desired, hitched to a horse or attached to a windlass for the purpose of obtaining the necessary power to operate the carrier.

Now when my hay-carrier is constructed 75 substantially as hereinbefore described it is operated in this wise: The load or hay fork, as shown in the drawings, by means of the clevis w, is attached to the traveling block H, the block for that purpose being on the floor 80 or wagon containing the hay or load to be elevated; and when the block H is in this lowered position the legs e of the latch E are engaged with the shoulders m on one side or the other of the double catch F, as the case may 85 be, and this engagement of the latch E locks the carriage C to the catch F, and that catch being fixed to the bracket h, which spans the track, as described; the frame C of the carrier is held firmly in position until the traveling block H, with its load is, by the power applied to the free end of the rope G, elevated till the openings v in the shell of the pulley H pass between the sides of the lower part f of the latch E, when the shell of the pulley H, 95 bearing against the lugs g on this lower part of the latch, forces outward the sides of the lower part f of the latch and inward the legs e thereof until these legs are disengaged from the shoulders m of the catch F, when the 100 spring c causes the sides of the lower part f of the latch to close upon the shell of the

pulley H and engage the lugs g with the openings v, so that the pulley H and its load are attached to the latch and supported by it. Then, the latch E being disengaged from the 5 catch F, the frame C, with its suspended load of hay, is free to travel, by means of its trolley-wheels B, along the track A to the position desired for unloading the carrier. The traveling of the carrier on its track is caused 10 by the horse or other power applied to the free end 3 of the rope G, and as the carrier travels the ends of the legs e of the latch E may pass on one side or the other of the catch F through the clearway n of that catch, 15 as may be desired. As is obvious, if the rope G were free at all times to render around the pulleys, the power applied to the rope would not move the carrier on its track. Therefore the enlargements y are provided at such 20 places on the rope G as will bring these enlargements in contact with the pawls p, locking for the time being the rope G and preventing its free rendering and causing the carrier to roll on the track A to the desired 25 point of unloading. The grip of these pawls may be regulated by the set-screws r, and they are permitted to yield, when not engaged with the enlargements y, through and by the action of the springs s. The enlargements y, 30 it must be understood, are not mere knots made in the rope G, but they are of ovoid form, so as to not only act as stops in connection with the pawls p, but also to offer no obstruction to the free passage of the enlargements around the pulley-wheels J J, &c. The 35 enlargements may be made by working in extra strands, or they may be of iron or wood riveted in place.

From the foregoing it will be seen that my 40 carrier may readily be caused to travel to the right or left with its load along its track, it being necessary only to apply the power for this purpose to either of the free ends of the rope G, passed around one or the other of the 45 fixed pulleys K K. When the power is applied to one of the free ends of the rope, the other free end may be made fast to its pulley K, and that pulley, by backing out its bolt from its clevis 2, be disconnected from its 50 screw-bolt u, so that the disconnected pulley may be drawn upward as the carriage travels, and so act as a counter-weight to take in the slack and keep taut the rope G, preventing loss of power.

55 When it is desirable to have several convenient points at which the hoisting of the load to the carrier may take place, I fix to the track A, or to the rafters, or to some other convenient objects, a number of brackets h, 60 and pivot to them the catch F instead of fixing that catch immovably in place. The catch so pivoted is shown in Figs. 4 and 5, and the object in pivoting it is to permit its being hoisted by a lanyard z out of the way 65 of the carrier, so that it will not trip the latch E as the carrier rolls past it to the posi-

tion at which it is desired to unload. By pivoting the catches in this way the load may be hoisted at as many places as there are catches in position, and yet these catches may 70 offer no obstruction to the free passage of the carrier from one end of the track to the other, if desired; or they may hold the carrier in position at each or any of the places where the catches are located. 75

Having now described my invention, what I claim as new, and desire to secure by Letters Patent, is—

1. In a hay-carrier, the combination of the carriage consisting of the frame C, supported 80 by trolley-wheels resting on the track A, the pulley-wheels D D, and the latch E, having the legs e e, extending above the rest of the carriage, and also having the lower parts f f, the catch F, with inclined edges k k, throat l, 85 and shoulders m m, supported above the track, the rope G, and the traveling pulley H, as and for the purpose described.

2. In a hay-carrier, the combination of the carriage consisting of the frame C, supported 90 by trolley-wheels resting on the track A, the pulley-wheels D D, and the latch E, composed of the two jaws, the spring, and the pivot-bar b, whereby the jaws are united and secured to the frame C, said jaws having the legs e e, extending above the rest of the carriage, and the lower parts f f, the catch F, with inclined edges k k, throat l, and shoulders m m, located above the track, the 95 rope G, and the traveling pulley H, as and 100 for the purpose described.

3. In a hay-carrier, the combination of the carriage consisting of the frame C, trolley-wheels, pulley-wheels D D, and latch E, having the legs e e, extending above the rest of the carriage, and the lower parts f f, the rope G, the traveling pulley H, and the catch F, with inclined edges k k, throat l, and shoulders m m, pivoted to a support above the track, and in one position engaging with the 105 latch E and in another position allowing the carriage to pass freely by it, substantially as and for the purpose described.

4. In a hay-carrier, the combination of the carriage having the frame C, pulley-wheels 115 D D, and pawls p p, and the rope G, having the enlargements y y, constructed and operating substantially as described.

5. In a hay-carrier, the combination of the carriage consisting of the frame C, having 120 the pawls p p, with stops r r and springs s s, the trolley-wheels, the pulley-wheels D D, and the latch E, having the legs e e, extending above the rest of the carriage, and the lower part f f, the catch F, with inclined 125 edges k k, throat l, and shoulders m m, located above the track, the rope G, having the enlargements y y, and the traveling pulley H, constructed and operating substantially as shown and described. 130

6. In a hay-carrier, the combination of the carriage provided with pulley-wheels D D,

the rope G, having the enlargements *y y*, the traveling pulley H, and the catch F above the track, the frame C of the carriage being constructed with lugs *a a*, to which are pivoted the pawls *p p*, having stops *r r* and springs *s s*, and which also form bearings for the pivot-bar *b* of the latch E, the legs *e e* of

which extend above the rest of the carriage and engage with the catch F, substantially as and for the purpose described.

JEROME A. CROSS.

In presence of—
D. A. CARPENTER,
C. E. FIELD.
